UNITED STATES PATENT OFFICE.

HENRY WEBER, OF NEW YORK, N. Y.

DESIGN FOR A TRIMMING FOR SILVERWARE OR SIMILAR ARTICLES;

SPECIFICATION forming part of Design No. 36,522, dated August 25, 1903.

Application filed July 14, 1903. Serial No. 165,533. Term of patent 3½ years.

To all whom it may concern:

Be it known that I, HENRY WEBER, a citizen of the United States, residing at No. 188 South Oxford street, borough of Brooklyn, city of New York, in the county of Kings and State of New York, have invented a new, original, and ornamental Design for a Trimming for Silverware or Similar Articles, of which the following is a specification, reference being had to the accompanying drawing, forming part thereof.

The drawing shows a plan view of my design.

What I claim as new, and desire to secure by Design Letters Patent, is—

The ornamental design for a trimming for silverware or similar articles substantially as shown.

In testimony whereof I have signed my name to this specification in the presence of two subscribing witnesses.

HENRY WEBER.
